ELECTRIC SWITCH

Harry A. Douglas, Bronson, Mich.

Application March 16, 1933, Serial No. 660,990

19 Claims. (Cl. 200—16)

This invention relates to electric switches commonly known as the push-pull type in which a reciprocable handle is pushed or pulled upon to establish the respective operative positions of the 5 switch.

Among other objects, the invention aims to provide an improved and novel construction for this type of switch. More specifically the invention includes an economical and positive construction of this type having three or more operative positions for a switch which may be employed as a dash switch for automotive vehicles in unitary controlling relation with the stop-light, parking lights and head lights of the vehicle, for 15 example.

Other objects and advantages will be apparent from the following description taken together with the accompanying drawings showing an illustrative embodiment of the invention, in 20 which—

Figure 1 is an elevational view of the illustrative switch, a mounting therefor being shown in section;

Figure 2 is an enlarged longitudinal section of 25 the switch of Figure 1 taken on the line 2—2 of Figures 4 and 6, and showing different operative positions of the switch in full and dotted lines;

Figure 3 is a cross-section taken on the line 3—3 of Figure 2;

Figure 4 is a cross-section taken on the line 30 4—4 of Figure 2;

Figure 5 is a partial longitudinal section similar to Figure 2 but showing still another operative position of the switch and taken on the line 5—5 35 of Fig. 7;

Figure 6 is a cross-section on a reduced scale taken on the line 6—6 of Figure 2;

Figure 7 is a similar cross-section taken on the line 7—7 of Figure 5;

Figure 8 is a similar cross-section taken on the line 8—8 of Figure 2 but showing in full lines the 40 positions shown dotted in Figure 2;

Figure 9 is a fragmentary longitudinal section taken on the line 9—9 of Figure 8 illustrating one 45 of the intaglio portions of the fixed contacts; and

Figure 10 is an end view of the switch taken from the bottom of Figures 2 and 5 on a reduced scale and showing illustrative circuits associated therewith.

50 Referring in detail to the figures of the drawings, the illustrative switch comprises a metallic cup-shaped casing 1 closed by a disc 2 of suitable insulating material secured to the casing as by means of tongue continuations 3 of the casing 55 received in and clinched within shouldered

notches 4 in the periphery of the disc 2. At its other end the casing 1 has a hollow bushing 5 riveted in and communicating with a central aperture in the end wall 6 of the casing. The bushing 5 may be externally threaded as at 7 and by 60 means of suitable clamping nuts 8 and 9 screwed on to the thread 7, the casing may be clamped to a mounting 10 which may be the instrument panel of an automotive vehicle. Desirably a spacing washer 11 is interposed between the nuts 8 and 9. 65 The washer 11 may also be slightly resilient to act as a lock member.

Reciprocable in the casing 1, I have shown a metallic shaft 12 which, in this instance, is of circular cross-section and has a slide bearing in 70 the bushing 5. The shaft also has at its other end a reduced extremity 13 which has a slide bearing in the central perforation 14 extending through the insulating closure disc 2. The shaft 12 is thus fixed upon an axis of reciprocation 75 substantially coincident with the axis of the casing. Upon the side of the instrument panel 10 facing the driver of the vehicle, the shaft 12 may conveniently have screwed thereon, as at 15, the knob 16 of insulating material which may be used 80 as a handle for reciprocating the shaft. To prevent rotation of the shaft it may have a longitudinal groove 17 in which is received an internal lug 18 in the bushing 5, these parts acting as keyway and key.

Upon an intermediate reduced portion 19 of the shaft 12 within the casing 1, I affix an insulating actuator comprising in this instance three discs of insulating material such as the two keeper discs 20 and 21 and the intermediate spacing disc 90 22 which are clamped between a shoulder 23 occurring where the intermediate portion 19 of the shaft 5 joins the main part of the shaft, and a riveted shoulder 24 which may be turned up at the other end of the shaft portion 19. A facing 95 washer 25 which may be of metal is advantageously interposed between the riveted shoulder 24 and the insulating discs, this washer being desirably of a diameter substantially smaller than the discs and in one position of the switch, the 100 washer is received in a countersink 26 in the inner face of the closure disc 2 surrounding the aperture 14 in which the shaft slides. To prevent rotation of the actuator discs 20, 21 and 22 on the shaft portion 19, this shaft portion is desirably flattened at its side 27 and the apertures 28 in the discs receiving the shaft portion 19 there-through are similarly shaped.

In the insulating actuator comprised by the insulating discs 20, 21 and 22, the discs 20 and 110

21 which are the outer discs, may be relatively thin and the intermediate disc 22 may be somewhat thicker and of smaller diameter than the outer discs 20 and 21, thus creating an annular 5 peripheral groove 29 in which is disposed a radially resilient metal split ring 30 which provides a movable contact for the switch, as presently described. To prevent rotation of the ring 30 with respect to the actuator, the ring may have 10 an inwardly directed lug (as by being bowed inwardly at 31) which is received in a notch 32 in the intermediate disc 22. The ring 30 is of slightly less width than the peripheral groove 29 as determined by the space between the discs 20 15 and 21, spaced abreast by the disc 22, so that the ring is loosely held within the groove and is free to have some moderate radial expansion under its own resiliency except as restricted by the fixed members next referred to, or may be free to shift 20 slightly.

These fixed members which cooperate with the ring 30 are here shown in the form of a plurality of metallic posts fixed on the insulating closure disc 2 and normally insulated one from the other 25 by this disc, the posts being spaced apart in parallel relation within the casing 1 about the axis of reciprocation of the shaft 12 so as to present surfaces which restrict the radial expansion of the ring 30. In accordance with my invention, these 30 posts include at least three, and in this case four, fixed contacts 33, 34, 35 and 36 complementary to the movable contact provided by the ring 30. These contacts may be advantageously formed 35 integrally with terminal members 37, 38, 39 and 40, respectively, extending upon the exterior of the casing and each riveted to the closure disc 2 as at 41. As in the illustrative circuit diagram 40 shown in Figure 10, the terminal 37 may be electrically connected by means of the insulated conductor 37a with the grounded battery 37b carried in the usual manner by an automotive vehicle; the terminal 38 by means of the insulated conductor 38a with the grounded head-lights 38b of the vehicle; the terminal 39 by means of the 45 insulated conductor 39a with the grounded parking lights 39b of the vehicle; and the terminal 40 by means of the insulated conductor 40a with the grounded tail light 40b of the vehicle. These insulated conductors may terminate in the usual 50 terminal plugs 41a which are yieldingly received in suitable apertures in the terminals 37 to 40, inclusive, in accordance with conventional practice.

In addition to the contact members, the posts 55 extending within the casing may include an abutment post 42, which may be conveniently riveted as at 43 (Fig. 2) in one of the notches 4, a small sheet of fiber or other insulating material 44 being desirably interposed in this notch between the 60 riveted metallic end of the post 42 and the tongue 3 which is also received in this notch. The post 42, which may not be as long as the other posts, may be advantageously located opposite the inward bend 31 in the ring 30, so that the grounded 65 corners 31a formed by the inward bend 31 just ride onto the post 42, thus restricting shifting of the ring in the "off" position of the switch, as presently pointed out.

70 The two outer insulating discs 20 and 21 comprised in the actuator are peripherally notched, as best shown in Figure 4 at 45, to receive the posts and permit the posts to slidingly engage the ring 30. Thus the ring normally provides a 75 bridging contact between such of these posts as

are electrical conductors, that is the posts 33 to 36, inclusive.

In accordance with my invention, certain of these posts have relief and intaglio portions thereon so staggered longitudinally that the ring 30 80 will be out of contact therewith in certain positions of the switch to discontinue a circuit there-through. In the position of the actuator shown in full lines in Figure 2, and also as shown in the cross-section in Figure 6, the ring 30 is in engagement with the contacts 34, 35 and 36, since in this position of the actuator the split ring is radially opposite, or longitudinally abreast, the relief portions of these contacts. As previously explained the inherent resiliency of the ring 30 85 maintains it in contact with these relief portions. By "relief portion", I mean the main portions of the posts which normally engage the split ring. In this position of the actuator, however, the ring 30 being longitudinally abreast of, or radially opposite, the intaglio portion 46 of the contact 33, is out of engagement with this contact and consequently is out of electrical engagement with the battery 37b. This therefore constitutes the "off" 90 position of the switch. In this position of the actuator since the contacts 34, 35 and 36 which are in engagement with the ring 30 describe a triangle which does not include the center of the ring 30 and the ring is therefore not restrained 95 at suitable points about its circumference by these contacts. I have accordingly provided the additional abutment post 42, already referred to, which, with the contacts 34 and 35, describes a triangle which includes the center of the ring, thus guarding against its expansion into engagement with the contact 33, or possible shifting of the ring into such engagement.

When the handle 16 is pulled upon to reciprocate the actuator to the position shown in Figure 5, and as shown in cross-section in Figure 7, the ring 30 is in engagement with the relief portions of the contacts 33, 35 and 36, but is out of contact with the intaglio portion 47 of the contact 34. Thus a circuit is established through the grounded battery 37b, terminal 37, contact 33, 100 ring 30, and (by means of the contact 35 and terminal 39) through the grounded parking lights 39b and (by means of the contact 36 and terminal 40) through the grounded tail light 40b. In this position of the actuator the contacts 33, 105 35 and 36 are suitably spaced about the center of the ring 30 to restrict it from expanding into engagement with the intaglio portion of the contact 34 and thus at this time no circuit is established through the head-lights 38b.

Next, when the handle 16 is pulled upon to move the actuator to the position shown in dotted lines in Figure 2, and as shown in cross-section in Figure 3, the ring 30 is in engagement with the contacts 33, 34 and 36, but is out of engagement 110 with the intaglio portion 43 of the contact 35 and thus a circuit is established through the grounded battery 37b, terminal 37, contact 33, and (by means of the contact 34 and terminal 38) through the grounded head-lights 38b and (by 115 means of the contact 36 and terminal 40) through the grounded tail light 40b, but not through the parking lights 39b, for the reasons already explained.

It will be noted that one of these contact posts, in this instance the contact post 36, is in engagement with the ring 30 in all positions of the switch, and this post is provided with detents in the form of annular ridges 49 spaced apart longitudinally, which cooperate with the resilient 120

ring 30 to yieldingly determine the respective operative positions of the switch. In other words, as the actuator is reciprocated, the ring 30 expands and contracts slightly so as to snap over the ridges 49, and there being two of these ridges, three operative positions of the switch are thus predetermined, each of these operative positions being longitudinally abreast of one of the intaglio portions of the other posts. Axial movement of the actuator beyond the three positions referred to, is of course positively limited by the wall of the switch casing 1 at one end and the closure disc 2 at the other end. The end wall 17a of the groove 17 may also act as a stop by being brought into abutment with the lug or key 18. To facilitate movement of the ring 30 over the ridges 49, these ridges are provided with cam surfaces 50 at each side thereof and extending longitudinally of the post. To further facilitate the camming action just referred to the longitudinally facing edges of the ring 30 may be beveled or rounded as at 51.

Although the ring 30 is restrained, as already described, from substantial expansion radially beyond the relief portions of the posts, should any slight expansion beyond these points, or shifting of the ring, take place, the relief portions of the posts are also provided with cam surfaces 52 which will cooperate with the rounded corners 51 of the ring to contract, or shift the ring sufficiently so that the axial movement of the ring and actuator will not be hindered but the ring will ride up the cam surfaces 52 and onto the relief portions of the posts for the purpose explained.

It will be understood that the ring 30 may constitute a relatively strong spring having very slight expansion and contraction but desirably having sufficient resiliency to make a good electrical contact with the conductor posts, and also to provide rather stiff resistance to movement past the detents 49 to definitely establish the operative position of the switch. The sliding engagement keeps the contact points bright.

In each case, where the effective contact surface of the posts is discontinued, as by the intaglio portions referred to, this surface is discontinued for an extent longitudinally of the posts equal to the axial width of the ring 30, and in register with one of the operative positions of the switch.

The axially extending inner walls of the casing 1 of the switch are desirably faced with an insulating liner 53 comprising a thin sheet of fibrous material, such as paper or the like, to guard against contact of the posts with the wall of the casing.

So constructed and arranged, my improved switch affords the advantages heretofore well known in a switch of the push-pull type, and, in addition, obviates the less advantageous characteristics of this type of switch readily lending itself, for example, to a structure involving more than two operative positions. At the same time, in accordance with my invention, the switch is sturdy in construction and positive in operation in each of its respective positions.

Having described my invention, I claim:

1. In a push-pull switch, the combination with a reciprocable actuator; of a radially resilient continuous contact bridge carried by the actuator; a plurality of fixed contacts radially disposed about the axis of reciprocation of the actuator, extending parallel thereto, and engageable by the movable bridge contact to be bridged thereby in one reciprocal position of the actuator one of

said fixed contacts at all times engaged by said bridge contact; and a detent carried by the last named fixed contact cooperating with the movable bridge contact to yieldingly maintain the respective reciprocal positions of the actuator.

2. The structure of claim 1 wherein said last named fixed contact centers the bridge contact upon the actuator between two other fixed contacts and wherein there is a cam surface on the detent cooperating with the movable contact to compress the movable bridge contact radially to permit axial movement of the movable bridge contact past the detent.

3. The structure of claim 1 wherein said last named fixed contact centers the bridge contact upon the actuator between two other fixed contacts in the bridging position of the movable contact and there are cam surfaces on the fixed contacts guarding against permanent axial abutment of the fixed contacts and movable bridge contact in axial movement of the movable bridge contact.

4. In a three position push-pull switch, the combination of a metallic casing; an insulating closure therefor; a metallic shaft reciprocable in the casing and having slide bearings in the casing and closure; an insulating actuator keyed to the shaft; an annular peripheral groove in the actuator; a metallic ring carried in the groove and providing a movable contact; a plurality of at least three metallic contacts fixed on said closure, said contacts being in the form of elongated posts radially disposed about the axis of reciprocation of the shaft and extending therealong in parallel relation normally in engagement with the movable contact; and axially staggered intaglio portions on the fixed contacts causing the movable contact to be spaced from the fixed contact the intaglio portion of which is radially opposite the movable contact in each axial position into which the movable contact is moved by reciprocation of the shaft.

5. In a three position push-pull switch, the combination of a reciprocable insulating actuator; an annular peripheral groove in the actuator; a metallic ring carried in the groove and providing a movable contact; a plurality of at least three metallic contacts insulated one from the other, said contacts being in the form of elongated posts radially disposed about the axis of reciprocation of the actuator and extending therealong in parallel relation normally in engagement with the movable contact; and axially staggered intaglio portions on the fixed contacts causing the movable contact to be spaced from the fixed contact the intaglio portion of which is radially opposite the movable contact in each axial position into which the movable contact is moved by reciprocation of the actuator.

6. In a push-pull switch having three or more operative positions, the combination with an insulating actuator reciprocable to said operative positions; of a radially resilient split ring carried thereby providing a movable contact; a plurality of at least three fixed contacts insulated one from the other, said fixed contacts being in the form of elongated metallic members radially disposed about the axis of reciprocation of the actuator and having surfaces normally in engagement with the movable contact, one of said members having its said surface discontinued in radial alignment with one position of the actuator whereby the movable contact is disengaged therefrom to discontinue a circuit therethrough; and a pair of axially spaced apart ridges on one of the members cooperating

with the movable contact to yieldingly determine the respective positions of the actuator.

7. In a push-pull switch, the combination with a reciprocable insulating actuator; of an arcuate movable contact carried thereby; at least three fixed contacts insulated one from the other, said fixed contacts being in the form of elongated metallic members radially disposed about the axis of reciprocation of the actuator and having surfaces normally in engagement with the movable contact, one of said members having its said surface discontinued in radial alignment with one position of the actuator whereby the movable contact is disengaged therefrom to discontinue a circuit therethrough.

8. In a three position push-pull switch, the combination with an insulating actuator reciprocable to three operative positions; of a radially resilient split ring carried thereby providing a movable contact; a plurality of at least four elongated metallic members radially disposed about the axis of reciprocation of the actuator and having surfaces normally in engagement with the movable contact, at least three of said members constituting fixed contacts insulated one from the other, each of said three members which constitute fixed contacts having its said surface discontinued in radial alignment with one operative position of the actuator whereby the movable contact is disengaged therefrom to discontinue a circuit therethrough, the said four members being so disposed that the movable contact is in engagement with at least three of the said members in each operative position of the actuator and each said three points of engagement describing a triangle including the axis of reciprocation of the actuator.

9. The structure of claim 8 wherein one of the members has axially spaced apart ridges thereon cooperating with the movable contact to yieldingly determine the respective operative positions of the actuator.

10. The structure of claim 8 wherein the actuator has a peripheral annular groove therein receiving the movable contact and wherein the actuator has peripheral notches therein receiving the said members in engagement with the movable contact.

11. In a push-pull switch, the combination with a reciprocable insulating actuator; of an arcuate radially resilient movable contact carried thereby; a plurality of at least four elongated metallic members radially disposed about the axis of reciprocation of the actuator and having surfaces normally in engagement with the movable contact, at least three of said members constituting fixed contacts insulated one from the other, each of said three members which constitute fixed contacts having its said surface discontinued in radial alignment with one operative position of the actuator whereby the movable contact is disengaged therefrom to discontinue a circuit therethrough, the said four members being so disposed that the movable contact is in engagement with at least three of said members in each operative position of the actuator and each said three points of engagement describing a triangle including the axis of reciprocation of the actuator whereby the

movable contact is restrained from expanding into engagement with the fourth member.

12. In a three position push-pull switch, the combination with a metallic cup-shape casing; of an insulating closure therefor; a bushing in the wall opposite said closure; a reciprocable metallic shaft passing through the casing and having slide bearings in the bushing and closure; an insulating actuator keyed to the shaft; an annular peripheral groove in the actuator; a radially resilient metallic split ring carried in the groove; a plurality of at least four elongated metallic posts fixed on the closure and radially disposed about the axis of reciprocation of the shaft in spaced insulated parallel relation within the casing; peripheral grooves in the actuator receiving the posts to be normally in engagement with the split ring whereby the latter provides a bridging contact between at least three of the posts; axially staggered intaglio portions upon at least three of the posts causing the split ring to be spaced from at least one of the posts in each three respective reciprocal positions of the actuator, one of the posts being in continuous engagement with the ring; and spaced apart annular ridges on the last mentioned post cooperating with the ring to yieldingly determine the three respective positions of the shaft.

13. The structure of claim 12 wherein there are cam surfaces between the posts and said ridges and between the posts and said intaglio portions engageable with the split ring to cause axial compression thereof in reciprocation of the shaft.

14. The structure of claim 12 wherein there are cam surfaces between the posts and said ridges engageable with the split ring in reciprocation of the shaft.

15. The structure of claim 12 wherein there is a longitudinal slot in the shaft receiving an internal lug in the bushing preventing rotation of the shaft.

16. The structure of claim 12 wherein the shaft is generally circular in cross section and wherein the portion of the shaft receiving the actuator has a flat surface mating with a corresponding flat inner perimeter portion of the actuator to prevent rotation of the actuator on the shaft.

17. The structure of claim 12 wherein the split ring is extended inwardly at one point in its circumference to be received in a notch in the peripheral groove of the actuator to prevent rotation of the ring on the actuator.

18. The structure of claim 12 wherein a short post is mounted on the closure to be engaged by the split ring in its position nearest the closure to center the ring on the actuator between two oppositely disposed fixed contacts.

19. The structure of claim 12 wherein the split ring is extended inwardly at one point in its circumference to be received in a notch in the peripheral groove of the actuator to prevent rotation of the ring on the actuator and wherein a short post is mounted on the closure to be engaged between the inward extensions of the split ring in its position nearest the closure to center the ring on the actuator between two oppositely disposed fixed contacts.

HARRY A. DOUGLAS.
